UNITED STATES PATENT OFFICE.

CARL McDERMOTT, OF FREEHOLD, NEW JERSEY.

ELECTRICAL COIN-DELIVERY MACHINE.

1,356,379.

Specification of Letters Patent.

Patented Oct. 19, 1920.

Application filed August 9, 1919. Serial No. 316,471.

To all whom it may concern:

Be it known that I, CARL McDERMOTT, a citizen of the United States, and a resident of Freehold, county of Monmouth, and

5 State of New Jersey, have invented a new and Improved Electrical Coin-Delivery Machine, of which the following is a full, clear, and exact description.

This invention relates to coin delivery machines, and more particularly to an electrically operated coin delivery machine.

An object of the invention is to provide a coin delivery machine for use in banks, merchandise establishments, and other institutions where silver coin is handled in making many change transactions.

It is a purpose to provide a coin delivery machine consisting primarily of a coin delivery unit electrically controlled by a key board unit, so that the cashier or operator of the machine may be distant from the coin delivery unit.

It is an object to provide a coin delivery machine which will properly function even though operated by unskilled persons. To this end the machine is so electrically controlled that the key board mechanism may be engaged for a long period of time without damage to the mechanism or without obtaining more than one cycle of operation. Or the key board may be instantly released, and yet the machine will complete its cycle of operation to deliver the correct amount of change. In fact, it is an object to produce a coin delivery machine inherently simple and positive in operation under all conditions.

A special feature of the coin delivery unit resides in the provision of means for automatically stopping the cycle of operation in case a coin becomes jammed or clogged in the machine. This machine will either positively deliver or eject all coins simultaneously, or it will not deliver any coins at all; in other words should one coin become clogged during the cycle of operation no delivery will take place, thus avoiding possibility of incorrect change being made.

A special feature of the machine resides in a release drive mechanism electrically operated. This release drive is interposed between an electric motor and the delivery mechanism and is employed to permit all parts to return to normal inactive position after one coin ejecting operation has been completed.

Another feature of the coin delivery machine relates to a plurality of jointly operating coin punchers operated simultaneously but separately selected to engage the coins 60 of desired denomination in order that any amount of change may be delivered.

A further feature resides in means for selectively lifting into position the desired coin punchers so that coin of required 65 denominational value may be ejected by said selected coin punchers.

Further objects and features relate to a combined electrical and mechanical means for executing the positive delivery of the 70 selected coins. To this end, there is employed a system of electro-selectively operated devices directly controlled from the distantly located key board which is operated by the bank cashier or other person. 75

The above enumeration points out many of the important objects of the invention, with reference to features of the mechanism. A practical example of a coin delivery machine is portrayed in the following description, 80 particularly pointed out in the appended claims, and illustrated in the accompanying drawings, wherein:

Figure 1 shows a perspective view of the coin delivery unit with the delivery chute 85 mounted thereon, and with a coin trough carried upon the machine. The coin delivery chute is arranged to deliver the coin on the front side of the machine, while the coin trough has its back turned toward the 90 front of said machine which places the coins carried in the trough away from the customer who receives coins from the delivery chute. The coin chute may be extended through the cage of the cashier's 95 office so the customer may readily receive the coin.

Fig. 2 points out a side elevation of the machine with the casing in section, or removed therefrom, so as to disclose the machine parts of the coin delivery machine. 100

Fig. 3 shows a back view of the machine, or a view looking toward the coins in the coin trough. This view is obtained by removing the rear wall of the casing, and 105 shows the solenoid selector means employed to select appropriate coin punchers, and shows parts of the driving mechanism.

Fig. 4 shows a plan view of the machine with the casing removed. This view discloses the plurality of coin punching arms located above the solenoid selectors, and the 110

power motor with parts of the power transmission.

Fig. 5 shows a fragmentary side elevation of the coin delivery mechanism. In this view the mechanism is in operation with a coin partly ejected from the trough ready to pass into the delivery chute.

Fig. 6 shows a view similar to that of Fig. 5. This is a side elevation, and a fragmentary view. The delivery mechanism has undergone partial operation but owing to the jamming of one of the coins the machine has automatically cut off its operation and is shown in a position ready to return to 15 normally inactive position.

Fig. 7 shows a sectional view taken upon the line 7—7 of Fig. 5. This figure relates to the mechanism employed for automatically cutting off the operation of the machine in case a coin jams or clogs at the outset of the operation.

Fig. 8 discloses a diagrammatic lay-out of the electric controlling system of the coin delivery mechanism. This figure shows the 25 electrical control elements connected with a preferred form of keyboard.

Fig. 9 shows a fragmentary detail view of the coin trough and ejector head mounted in guided relation with said trough, and 30 Fig. 10 shows a view taken upon the line 10—10 of Fig. 9.

It is desirable to employ an effectively operating key board selector unit with the coin delivery unit. To this end I have disclosed the design of a keyboard constituting an invention separate from the one here-with presented. This key board selector unit is disclosed in an application for patent filed in the United States Patent Office 40 on the 9th day of August, 1919, under the Serial No. of 316,470.

In the present application, and in Fig. 8, is shown a diagrammatical layout of a bank of electrical contact bars which constitutes 45 the subject matter of the aforesaid application pointed out by the cross reference.

In constructing a machine under the specifications and claims of this disclosure, I employ an inclosed casing in which is 50 mounted an electric motor or other power means. A coin holder trough is mounted on the upper portion of the machine and provided with a number of grooves into 55 which the cashier or operator will place stacks of coins arranged in order of denominational value. There is employed a plurality of jointly operating coin punchers which function to eject a single coin with each puncher from each stack of 60 coins. Electro-selective means are employed for each individual coin puncher in order that one or more punchers may be lifted in position so as to eject a coin as it travels forward.

65 Referring now more in particular to the

views for structural description and operation, wherein the same machine parts are designated by the same reference characters throughout, the numeral 1 points out a base fitted with pads 2. The base is provided 70 with a casing comprising side walls 3 and a top 4. A delivery chute is secured to the side of the machine and consists of a tube 5 secured vertically to one side or face of the casing. The upper portion of this chute 75 is open and connects with the delivery mechanism confined within the casing, while the lower portion of the tube curves outwardly in position to deliver coins to the recipient. The coin delivery opening of 80 the chute is indicated by the numeral 6. Upon the upper portion of the casing is fitted a coin trough 7. This coin trough is provided with a number of trough grooves cut in the face thereof into which are placed 85 stacks of coins. The coin trough will preferably have about the same number of coin grooves or receptacles as there are denominational values of coins in circulation. The trough 7 will preferably be mounted on the 90 machine in such a manner as to make it easily removable to facilitate manufacture and assembly.

A pair of frames 8 are erected vertically on the base and spaced apart. Each frame 95 is provided with a journal 9 integrally formed on the upper part of the frame or leg members 8. The legs 8 of the frame are secured to the base by bolts or screws. The two journals 9 rotatably mount a main rock 100 shaft 10. A gear sector 11 is associated with the rock shaft and adapted to rotate therewith during operation of the machine; but so connected as to move freely thereon should a coin become jammed during a cycle 105 of operation. The gear sector 11 is formed integrally with a hub 12, the hub 12 being journaled upon the rock shaft. An arm 14 is integrally formed with a hub, the hub being fixed upon the rock shaft 10 by a pin 110 15 or other appropriate means. The arm 14 and gear sector 11 are positioned adjacent 115 each other on the shaft with a little space left between the arm and the gear sector. A stop pin 16 is fixed to the gear sector, and adapted to freely pass by the arm 14 in the space left between the arm and said gear sector. The lower portion of the arm 14 is provided with a reach-bar 17, and on the outer end of this reach-bar is made a hook 120 18. The reach-bar 17 lies adjacent the rim of the gear sector with the hook 18 turned back to engage the edge of said sector and lying in contiguous relation therewith. Referring to Fig. 5 the arrow indicates the 125 direction of rotation of the shaft 10, and it is seen that the gear sector 11 may rotate in the direction indicated by the arrow without necessarily moving the arm 14, but the arm 14 cannot move in the direction of the 130

arrow without carrying the sector with it due to positive engagement of the hook 18 with the sector 11. A coil tension spring 19 has one end thereof connected with the 5 arm 14 and the other arm thereof connected to an adjustment rod 20. This adjustment rod is pivoted upon the forward portion of the gear sector as designated by 21 and travels with the sector. A boss 22 shown in 10 Fig. 2, is made on the hub of the gear sector, and in this boss is formed a hole in which is slidably mounted a screw threaded member 23. This member is connected to the adjustment rod 20 through a pivot pin 15 24. A nut 25 is employed to adjust the member 23 back and forth in the boss 22. In this manner the adjustment rod 20 is moved about its pivotal point 21, which tightens or loosens the spring 19 according 20 to the desired adjustment of the mechanism. The spring 19 will have sufficient tension to confine the arm and gear sector in joined movable relation during the operation of the machine, but will have sufficient resilience 25 to permit the gear sector and arm to move relatively one upon the other should any portion of the coin delivery mechanism become locked or clogged as hereinafter described.

30 A drive shaft 27 is employed to rotate the gear sector, and to accomplish this a worm 28 is fixed to the drive shaft 27. The drive shaft is supported at one end thereof by a journal bearing 29. This bearing 29 is carried between a pair of lifting arms 30, said arms being spaced apart and pivoted at 31 upon a support 32. The support 32 is fixed to the base 1 of the machine. The upper ends of the lift arms are provided with a pivot 33 which permits the lifting arms 30 to swing about the pin 31 to slide the bearing 29 along the shaft 27. A solenoid 34 is fitted with a guide tube 35, and a solenoid plunger 36 is slidably confined within the guide tube. The plunger is bifurcated at the end thereof and provided with a pivot pin 37 joined with a link 38. The other end of the shaft 27 is fitted with a knuckle 39 which connects with a 45 universal joint formed in the end of a main shaft 40. This shaft 40 is journaled in a standard 41 secured to the base 1. The shafts 27 and 40 are, therefore, connected one with the other through a universal joint 50 which permits the outer end of shaft 27 to be swingable up and down in order that the worm 28 may be engaged with the gear sector 11. The solenoid 34 and associate parts exercise a control over the shaft 27 to engage 55 the worm with the gear sector. The views 5 and 6 show the gear sector and worm in operative engagement. This engagement is maintained by virtue of energization of the solenoid 34 which draws the 60 plunger 36 inwardly to swing the shaft 27 upwardly until the worm and gear are engaged. This movement of the solenoid is executed against the tension of a spring 42. This spring has one end thereof connected to the bearing 29 and the other end thereof 70 connected to the support 32. When the solenoid 34 is deenergized the tension of the spring 42 acts to return all parts to normal position by pulling the bearing 29 outwardly on the shaft, which disengages the 75 worm and gear sector, as shown in Fig. 2. The means of controlling the energization of the solenoid 34 will form the subject of a later description within this specification. A sprocket 44 is fixed to the shaft 40. 80 Means for transmitting rotation to the sprocket 44 and thus operating the above described mechanism will now be described.

An electric motor 46 is secured to the base 1, and a sprocket 47 is fixed to the motor 85 shaft. A chain 48 is confined on the sprockets 44 and 47 to transmit rotation to the shaft 27. The operation of the motor is controlled from a key board remotely located from the coin delivery unit, said operation 90 being carried out when the circuit through the motor is closed by the operator to deliver coins to the chute. In order to limit the motion of all parts, a pair of stops 136 are fixed to the frame. A swinging arm 135 95 is fixed to the shaft 10 with the lower end of said arm disposed between the stops 136. These parts are shown in Fig. 2. When the swinging arm 135 has engaged the uppermost stop the machine rests supported in 100 that position until another cycle of operation is carried out. A pin 137 is fixed to the shaft 10, and a tension spring 135 has one end thereof attached to the outer end of the pin 137, and the other end thereof attached 105 to the base or some part of the frame so as to draw the mechanism into rearwardly limited non-operative position against a stop 136. The spring acts to hold the machine in inactive position ready to undergo 110 operation. When the machine undergoes a complete cycle, the swinging arm 135 engages the lowermost stop 136 which stops the travel of the machine in that direction simultaneously with the disengagement of 115 the worm 28, which permits the spring 138 to return the parts to normally inactive position. The above complete description covers the assembly of parts from the motor through the transmission to the shaft 10. 120

Upstanding arms 50 are fixed to the rock shaft 10. The arms 50 are spaced apart and preferably fixed to shaft 10 near each end of said shaft. A rod 51 is fixed in the upper ends of the arms 50. The parts 50 and 51 125 mount a plurality of coin punch arms employed to selectively eject the required amount of coins from the machine. The several coin punchers are designated by the reference characters 5^c, 10^c and 10^c, 25^c and 130

50°. These coin punchers consist of a rod one end of which is fitted into a hub extension 52, shown in Fig. 4, said hub extension being integrally made with a bearing 53. 5 The bearing 53 is journaled on the rod 51 which permits the coin punchers to pivot thereabout. On the free end of each coin puncher is fixed an ejector head adapted to engage a coin as the coin punchers travel 10 forward. This member consists of a finger 54 integrally formed with a guide 55, as shown in Figs. 9 and 10. Since each coin puncher is pivoted on the shaft 51, the ejector heads may be raised or lowered into operative engagement with the coins in the 15 trough as later seen.

A guided relation exists between each ejector head and the coin trough 7. The coin trough 7 is provided with a coin support 20 plate 57 which is fixed to the lower edge of the upstanding trough member 7. The coin plate 57 is provided with a slot 58. The slot 58 is approximately the width of the finger 54 of the ejector head, and said ejector 25 head is slidably confined in slot 58. The upper face of the guide 55 moves contiguously with the underneath face of the coin plate 57. A coin ejector slot 59, as shown in Fig. 2 is formed in the lower portion of the 30 trough just above the coin plate 57. Coins may be punched through the slot 59 by the coin punchers, as later seen. The aforescribed chute 5 passes through the casing and a coin chute 60 is mounted adjacent the 35 lower portion of the coin trough. This coin chute 60 opens directly to the coin slot 59. The delivery chute 5 and the coin chute 60 are connected so that a coin which drops into the chute 60 will pass directly to the 40 delivery chute 5. Thus the chutes 60 and 5 connect together to form a continuous tubular member through which the coin passes until it is discharged at the mouth 6 of the delivery chute. In order to hold the coins 45 in positive position prior to the ejecting operation there is employed a retaining ball 61, as shown in Fig. 9 which is movably confined in a bore formed in the trough member. A spring 62 is placed in the bore back 50 of the ball to press the ball normally downward into engagement with the upper face of the coin plate 57. This retaining ball 61 is mounted forward of each coin groove and prevents a coin from passing through the 55 slot 59. When, however, a coin is thrust forward under the ejecting impulse of a coin puncher the ball 61 will be displaced upwardly, which permits said coin to be ejected through the slot 59. 60 As above described, means is provided to hold the coin punchers and ejector heads in operative engagement within the coin plate. To this end solenoids are employed to lift each coin puncher upwardly until the finger 65 54 is in line with the rim of the coin. Fig.

2 shows the ejector head in downward position prior to being lifted in line with the coin. Fig. 5 shows one coin puncher in upwardly limited position engaged with the rim of a coin and ready to eject said coin 70 from the coin trough into the chute 60.

A number of solenoids designated in the drawings by 64, 65, 66, 67 and 68 are individually placed under each coin puncher and function to lift the coin punchers into 75 operative punching position. These solenoids are respectively arranged to operate the coin punching members 5°, 10° and 10°, 25° and 50°. Each solenoid consists of an electro magnetic coil fitted with a tubular 80 guide 70. The tubular guide 70 projects from the lower end of the magnetic coil 69 and passes through a hole formed in a horizontal support tube 71. This tube 71 is disposed between the two frame legs 8, and 85 has each end thereof fixed to the frame legs which supports the tube 71 in fixed position as a part of the frame upon which the device is assembled. The tube 70 is provided with a solenoid plunger 72. The upper end of 90 this solenoid plunger is fitted with an insulating head 73 which is fixed to the upper reduced end of the plunger 72. This head is provided with a shoulder which seats against the upper end of the tube and thus 95 limits the downward movement of the solenoid plunger. The lower portion of the plunger 70 is knurled or grooved. This provides a roughened or irregular cylindrical surface. A hole is drilled through the tube 100 71 and the guide 70. These holes register one with the other, and a locking head 74 is slidably mounted in the registered holes with the forward end thereof in a position capable of frictionally engaging the knurled 105 surface of the plunger 72. The head 74 is provided with a stem 75 upon which is confined a coil compression spring 76. A shaft 77 is horizontally pivotally arranged between the two support frames 8. This shaft 110 77 has fixed thereto a depending arm 78, and in the lower portion of this arm is provided a hole 79. The outer end of the stem 75 is loosely retained in the hole 79 with the spring 76 confined on the stem between the 115 arm 78 and the head 74. Thus as the shaft 77 is slightly rocked or rotated the spring 76 undergoes compression and thrusts the head 74 in close frictional engagement with the knurled surface of the plunger 72. The shaft 77 is likewise fitted with a lifting arm 80 fixed thereto. The outer end of the arm 80 is bent horizontally, as shown in Fig. 4 which provides a finger 81 to engage a lifting cam, as later described. It is now seen that the lifting arm 80 may be actuated to control the engagement of the locking head 74 with the plunger 72. The compression spring 76 will be so adjusted that it will hold the head 74 at rest in the tube 71 with- 120 125 130

out engaging the knurled plunger, this being the normally inactive position of parts. The above description is directed to one of the solenoids employed for controlling the lifting operation of the coin punches. Each solenoid is provided with the plunger and locking means as described. The shaft 77 and the lifting arm 80 are common to all of the solenoids, while an individual arm 78 is employed for each separate solenoid so that the plungers of all solenoids will be locked when the machine is in operation, and released when the machine has completed its work.

15 An upstanding rod 83 is fixed in the shaft 10, and adapted to move with this shaft. The upper end of this rod is shaped to function as a cam to lift the arm 80. The rod 83 has a horizontal bend 84 as shown in Fig. 4 right angular with the body 83, and the bend 84 is shaped on an upward curve as shown at 85 as shown in Fig. 5. The upwardly curved extremity 85 is arranged in line with the finger 81. A rod 86 is integrally made with the lift arm 80. This rod 86 is arranged approximately vertical with the upper end thereof reduced in size and bent over in the form of a hook and welded to the lift arm. The upper end of 25 the rod 86 is shaped in the form of a hook so as to space said rod apart from the arm 80 in order that the cam 85 may have freedom of movement in its backward and forward direction to engage and disengage the lift arm 80. The lower end of the arm 86 is bifurcated to receive the upper end of a solenoid plunger 87. The upper end of the plunger 87 is flattened and slotted, as shown in Fig. 2, and slidably confined in the fur- 30 cation of the rod 86. A pin is employed to attach the rod 86 and plunger 87 together. The slot allows slight lateral motion of either member in order to avoid cramping of parts during operation. This plunger 87 is slidably confined in a solenoid 88. This solenoid is supported on a post 88^a. When energized the solenoid will discharge the plunger 87 upwardly to lift the arm 80 so the finger 81 will be above the cam 85. Thus 35 when the arm 80 is lifted in upward position the cam 85 in its forward travel will engage the underneath side of the finger 81 which thrusts the heads 74 against all of the solenoid plungers. When this operation takes 40 place all of the plungers 72 are clamped irrespective of their position. All or a part of the plungers 72 may be in an upwardly limited position or may be down, and in either case they are clamped and held during the time the solenoid 88 is energized while the shaft 10 is traveling in its cycle of partial rotation.

A bracket 90 as shown in Fig. 5 is fixed to the base and mounts a yoke 91. A solenoid 92 is mounted in the yoke 91, and a

solenoid plunger is slidably carried within the solenoid and guided by the yoke. The solenoid core consists of a plunger 93 mounted on an iron rod 94, said rod provided with a weight 94^a fixed to the lower end 70 thereof. The plunger is fitted with a brass rod 96 upon the upper end of which is mounted a fiber head 97. It is preferable to employ brass for the rod 96 while iron will be used for the rod 94. This will cause 75 the solenoid core to properly function by moving upwardly when said solenoid coil is energized.

The solenoid just described is employed to automatically break or open the main circuit 80 after said motor has completed its cycle of operation. To this end, a switch comprising contact bars 98 and 99 is mounted on a fiber base 100. The bar 98 is pivoted on the insulating base, while the contact bar 99 85 may be fixed to said base. Each contact bar is provided with contact heads, and the one member 98 is somewhat longer than its companion contact bar, which arrangement positions the head 98 of the solenoid directly underneath the end of the circuit breaker member 98. A lever 101 is pivoted upon the fiber base and one end thereof remains in normal engagement with the underneath face of the head 98. By pivoting the lever 101 95 the contact head 98 will pivot the switch part 98 upwardly and away from the switch part 99 breaking the electrical circuit main as later seen. A circuit breaker arm 102 is fixed to the rock shaft 10, with the outer end 100 thereof disposed in line with the outer end of the lever 101. When the rock shaft 10 rotates, the circuit breaker arm 102 tilts the lever 101 so as to thrust the solenoid plunger and head 98 upwardly to part or break 105 the circuit switch 98-99. The mechanism just described functions as a mechanical circuit breaker and comes into operation simultaneously with the completion of the coin punching action of the machine.

An auxiliary means is employed for opening the circuit breaker or circuit parts 98-99 in case a coin jams or in case the machine does not properly function. In order to accomplish this a circuit breaker 115 arm 104 as shown in Figs. 2 and 6 is pivoted on the frame at 105. A counterbalanced weight 106 is attached to the circuit breaker arm 104 to keep the bifurcated end 107 in upwardly limited position. The reference numeral 105 designates a shaft or rod which is horizontally journaled in the frame by having one end thereof journaled in the standard 41, while the other end thereof is journaled in the bracket 90. The circuit breaker arm 104 is fixed to one end of this shaft 105, while the other end of the shaft is provided with a breaker arm 108 as shown in Fig. 4 which has its outer end bent in the form of a lift finger 109, said lift finger ter- 120 125 130

minating in a position under and forward of the pivotal point of the lever 101 as shown in Fig. 6. Thus when the shaft 105 is partially rotated by swinging the circuit breaker arm 104, the arm 108 tilts upwardly the lever 101 which thrusts the head 97 against the circuit breaker 98 thereby opening the circuit. A depending rod 110 is pivotally mounted at 111 on the arm 14. The numeral 111 5 designates a pin fixed to the depending rod and pivotally mounted in the arm 14. The inner end of the pin 111 is provided with an arm 112 fixed thereto. The parts 110, 111 and 112 comprise a swinging member, 15 the upper portion 112 of which is mounted on the inside of the arm 14, while the lower member 110 is mounted on the outside of the arm 14 and freely swings about the pivot. The arm 112 is mounted in line with the stop 20 pin 16 so that said stop pin will engage said arm in case there is relative movement between the arm 14 and gear sector 11.

The mechanism described in the preceding paragraph provides a safety circuit breaking 25 means which is automatically brought into use in case a coin jams. By referring particularly to Fig. 6 it is seen how that coin puncher is engaged with a coin which has become jammed in the trough and fails to 30 eject through the slot 59. When this occurs, which occasionally will, due to bent coins or other irregularities, the gear sector 11 moves forward under the driving impulse of the electric motor, and being freely 35 journaled on the shaft 10 does not move the coin punching mechanism. The coin punchers are moved only when the arm 14 is carried forward during rotation of the gear sector, and since the coin punchers are 40 locked against movement the spring 19 undergoes tension and stretches until the stop pin impinges the arm 112. This throws the depending rod 110 forward to trip the circuit breaker arm 104 which opens the 45 motor circuit thereby stopping said motor.

The worm gear will be disengaged and the spring 19 cause the parts to return to normal inactive position. When the worm 50 disengages the sector, the hook 18 on the reach-bar stops the movement of the gear sector, and the spring 19 is so adjusted as to remain under sufficient tension to cause the hook 18 to continuously engage the face of the gear sector. Thus the gear sector and 55 the arm 14 are joined together through the spring 19, which spring forms a yieldable connection between the transmission and the coin punching mechanism. This yieldable connection prevents damage and breakage 60 of parts when the machine fails to function due to jamming of coins or other imperfect functioning. During normal operation, and when the coins are readily ejectable from the machine, the spring 19 is sufficiently 65 strong to move the arm 14 along with the

gear sector when said sector undergoes rotation.

The electric motor circuit, and other circuits necessary to energize the several solenoids employed, are under direct control of 70 the operator. When a selected key is depressed the motor circuit and appropriate solenoids become energized. The electric motor must necessarily undergo one complete operation, or cycle, in order that the 75 coins will be punched from the trough and ejected through the chutes. The operator may occasionally hold the key down to close the circuits sufficiently long to complete the 80 cycle of operation, but quite often the operator might fail to hold said key down sufficiently long to complete the operation. Means are provided for automatically bringing 85 into operation an independent circuit which furnishes current to the motor until said motor has completed its cycle of operation. This independent circuit functions regardless of the length of time the operator holds down the key.

To this end there is employed a relay 90 114, as shown in Figs. 3 and 4. This relay is supported on a suitable bracket 115. The relay more clearly appears in the diagrammatic view of Fig. 8 where the electromagnet is shown with a contact head, and an 95 armature pivoted at 116. The armature 117 is provided with a weight so as to keep this armature and contact head normally disengaged from the contact head on the electromagnet 114 when said magnet is deenergized. The upper portion 118 of the armature is also provided with contact points and joins with the main supply line through a circuit 131 employed to furnish current to this machine. The circuit wire 131 connects with the relay magnet 114, and also connects with the relay armature. The other end of this circuit wire 131 connects with an electric current main 124 which supplies the motor. Therefore, when the relay 100 114 is in closed position, as shown in Fig. 8, the current from the battery 119 flows to the motor through the independent circuit wire 131 which furnishes current to the motor regardless of the position of the key, 115 whether said key is disengaged or engaged. This circuit 131 may be termed an independent circuit arranged in parallel with the electric current main 120, and so termed independent by virtue of its ability to 120 furnish current independently of the key board, for running the motor. In case the key is engaged with the contact bars the current will divide and flow through the circuit wires 120 and 131, but in case the key is 125 disengaged from the circuit bars, then the current will flow to the motor through the wire 131. Therefore, if the operator releases the key 95 before the cycle of operation is completed, the relay 114 and inde- 130

pendent circuit 131 functions to supply the motor until the operation of the machine has been completed.

A battery or other source of current 119 supplies the main circuit line 120. This circuit line 120 connects with a key board. Another section of the current main is designated by 122 which connects the other side of the battery with the circuit breaker 10 98. A section of current main 123 connects with the circuit breaker and connects in parallel with the plurality of solenoids 64, 65, 66, 67 and 68. This arrangement places the circuit breaker 98—99 in series 15 with the electric current main. A circuit wire 64^c connects with the solenoid 64, a circuit wire 65^c connects with the solenoid 65, and likewise circuit wires 66^c, 67^c and 68^c connects with the solenoid 66, 67 and 68 respectively. A circuit wire 124 connects with the electric current main 123, this electric circuit 124 has connected in series therewith the electric motor 46. A circuit wire 125 connects in parallel with the motor supply 20 circuit 124, said circuit wire 125 joining with the solenoid 88 to energize same during the time the motor runs. Likewise the solenoid 34 connects in parallel through the circuit wires 126 to the motor circuit 124. 25 30 A key board is employed for operating the coin delivery mechanism. This key board comprises a plurality of contact bars which are fitted with suitable keys so that the operator may depress the appropriate 35 key in order to close the circuit through the proper electro control elements so that the correct number of coins may be discharged from the chute. A ground plate 127 is provided with a plurality of key elements. One 40 of the key elements is shown in Fig. 8 and designated by 95. This key comprises the button 95 formed on the upper end of the rod 128. The number 95 printed on the button indicates the amount of change which 45 will be delivered when the button is depressed, and the key board will be provided with a number of keys ascending in value in multiples of 5 to 100. Hence the operator may deliver change as desired from one 50 five cent piece up to one dollar.

Contact bars 5^b are employed in the key-board and connect with the circuit wire 64^c. The several contact bars 5^b are, therefore, connected directly to the solenoid 64 which 55 controls the operation of the coin puncher 5^c. A bridge 5^a, diagrammatically shown, joins the several contact bars 5^b, and the circuit wire 64^c connects to the bridge.

A number of contact bars 10^b are shown 60 and joined together by a bridge 10^a, and the circuit wire 65^c connects to the bridge 10^a. This arrangement places the solenoid 65 in electrical connection with the bars 10^b.

A number of contact bars 50^b are used in 65 the key board and joined together by a

bridge 50^a, and the circuit wire 68^c is connected with the bridge 50^a. This places the solenoid 68 in electrical connection with the contact bars 50^b.

A number of contact bars 25^b are shown 70 in the key board joined together by the bridge 25^a. This bridge is in direct electrical connection with the solenoids 67 through the circuit wire 67^c.

Thus the key elements shown in Fig. 8 are 75 arranged in groups, each group being connected to its individual solenoid in order that said solenoid may be energized to lift the coin puncher if current flows from any one of the bars of that particular group. 80 The rod 128 is disposed between two vertical banks of contact bars. The rod is provided with contact balls or points which engage the desired contact bars. In this instance the key is designated by 95 which in fact 85 means that 95¢ will be delivered from the coin punching mechanism when said button is depressed. In order that 95¢ in silver be delivered it will be necessary that the mechanism deliver one 50¢ piece, one 25¢ piece, 90 and two 10¢ pieces. To this end the key rod 128 is fitted with contact balls or points which will engage two of the 10^b contact bars, and one of the 25^b contact bars and finally one 50^b contact bar. When the key 95 is depressed into position shown the contact points engage said bars thus connecting up the solenoids 65, 66, 67 and 68 with the key board. The rod 128 transmits the current from the ground plate 127 upwardly 100 to distribute said current through the various contact bars. The electric current main 120 connects with the ground plate and feeds upwardly through proper contact bars until the desired solenoids are energized to lift 105 the proper coin punchers into operative position. The key and rod 128 in Fig. 8 are shown depressed so that the contact balls are engaged with the bars. The lower end of the rod 128 may have fixed thereto one end 110 of a coil spring, not shown, while the other end of said spring is fixed to the plate 127. A tubular casing 130 is fixed to the ground plate and may have the spring above referred to concealed within said tube. This 115 arrangement of parts will cause the key rod 128 to remain normally upward when in inactive position, since the coil compression spring will function to return the rod 128 upwardly and disengage the contact balls as 120 soon as the operator releases the button.

A plurality of contact bars 46^m are also employed in the key board and joined together by a bridge 46^a. The motor circuit wire 124 is connected to the bridge 46^a. 125 This places the motor 46 in series with the key board and electric current main 120. The rod 128 also has a contact ball which engages one of the bars 46^m, and when so engaged the current is transmitted upwardly 130

from the plate 127 through the bar 48^m, through the bridge 46^a to the motor, and thus completes the circuit through the electric current main to said motor.

5 A circuit wire 132 connects with the electric current main 122, said circuit 132 including the solenoid 92 in series therewith. This circuit 132 connects with contact bars 92^m. The key rod 128 is fitted with a contact ball which will engage the contact bar 92^m when said key is depressed to start the machine in operation. Thus the solenoid 92 is in series with the key board and electric current main. The contact bars 92^m are 10 preferably somewhat deeper than the other contact bars constituting the key board. This provides a longer contacting area on the contact bars 92^m than is provided on the other contact bars. The bar 92^m has its bottom edge even or in the same plane with the bottom edges of the other contact bars which causes the upper edge to be spaced somewhat above the upper edge of the narrower bars. Thus when the key is depressed a contact 15 ball engages the bar 92^m before any of the other bars are engaged. This action causes instant energization of the solenoid 92 slightly prior to the energization of the other electrical elements of the system. 20 25 Likewise this construction causes the solenoid 92 to be the last member deenergized when the key is returned to its upwardly disengaged position. When the circuit is closed through the bar 92^m by punching the button 95 downwardly, the current flows 30 from the battery 119 through the key board, and through the solenoid 92 and back to the battery. This energizes the solenoid 92 and holds the plunger 93 in a secured position downwardly in contact with the lower portion of the coil. After the electric motor 35 has completed its run to operate the coin punching mechanism, the circuit breaking means 102 impinges downwardly on the lever 101 which thrusts the plunger 93 upwardly against the magnetic pull of the solenoid coil 92. At this instant of operation, the plunger 93 firmly adheres to the upper portion of the solenoid coil due to the 40 magnetic attraction thereof, and due to the fact that the plunger 93 has been forced upwardly past the magnetic center of the solenoid. Thus the circuit breaker 98 is held in upward and open position due to the 45 mechanical breaking of said circuit when the breaker arm 102 impinged the lever 101.

The foregoing paragraph described the 50 operation of the machine when the cashier or operator holds the key 95 down for a longer period than is necessary to cause the machine to function. It often occurs that an operator may press the key downwardly and hold the circuit closed, and in such case it becomes necessary that the circuit be 55 mechanically broken in order that the machine

will not undergo a repetition of coin punching actions. The mechanical circuit breaking means, consisting of the elements 98, 101, 102, and others, are specially employed for the purpose of opening the circuit and stopping the electric motor when the operator inadvertently and unnecessarily holds the key down. After the breaker arm 102 impinges upon the lever 101, said arm 102 will return to normal position and release the 70 lever 101. Even though the lever 101 is released the lifting head 97 will remain in upward position and keep the circuit 122-123 broken, due to the continued energization of the solenoid 92 as long as the operator holds 80 the key down. Thus the means described will positively prevent the machine from functioning more than one time. Even though the operator holds the key in depressed position long after the coins are 85 delivered, the machine will not undergo operation again until the key is released and punched for another coin ejection movement.

A partial description of the operation of 90 the coin delivery mechanism has been given. A complete recitation of the simultaneous energization of the various solenoids and other electrical elements will now be taken up. It will be assumed that the machine is 95 in inactive position and the button 95 in Fig. 8 is depressed to discharge 95¢ in silver to a customer through the chute 6. Instantly the key goes downwardly, the contact point on the rod 128 engages one of the 100 circuit bars 92^m which energizes the solenoid 92 and attracts the plunger 93 downwardly so as to securely hold the head 97 out of engagement with the circuit breaker 98. When the key 95 has been depressed, the circuit wires 65°, 66°, 67° and 68° are brought 105 into direct electrical connection with the electric current main 120. This action energizes the solenoids 65, 66, 67 and 68, since said solenoids are connected to the battery 110 through the wires 122 and 123. The energized solenoids instantly discharge their plungers upwardly and lift the coin punchers 10° and 10°, 25° and 50° into position 115 within the slot of the coin plate. The rod 128 also engages the contact bar 46^m which closes the circuit through the electric motor 46 and starts same to running. Simultaneously with this action, the solenoids 34 and 88 are energized. When the solenoid 34 is 120 energized, the worm 28 is engaged with the gear sector 11, and likewise the solenoid 88 functions to lift the arm 80 upwardly so that the cam 85 may engage the finger 81. The motor is now running, which causes the 125 gear sector to travel forward pulling with it the arm 14. The arm 14 rotates the shaft 10 which causes the coin punchers to move forward in their respective slots in the coin plate until the rim of a coin is engaged. 130

The coin punchers continue to move forward with the coin thrust against the retaining ball 61 which moves upwardly from the path of travel of the coin thus permitting the coin to be ejected into the chute 60. Thus four coin punchers have moved forward and two 10¢ pieces, one 25¢ piece, and one 50¢ piece have been ejected into the chute 60. The 95¢ button was not provided 10 with a contact ball which closed a 5^b contact bar, hence the solenoid 64 was not energized and a 5¢ piece was not ejected.

When the button 95 was depressed, the current was passed through the relay 114 which 15 attracted the armature 117 to close the contact heads on the member 118. This action on the part of the relay 114 closed the independent circuit 131 from the battery to the motor. Thus current is supplied directly 20 from the battery to the motor, and the solenoids which were energized at the time the button was depressed. In case the operator released the key 95, the operation of the mechanism will not be discontinued. The 25 motor, therefore, runs until the circuit is mechanically broken. The opening or breaking of the circuit is effected through the circuit breaker means hereinbefore described consisting of the circuit breaker 30 arm 102.

Assume now that a bent coin becomes jammed or clogged, which prevents the machine from functioning. If one coin clogs, none of the coins will be ejected; because if 35 one coin puncher is prevented from completing its punching movement, all coin punchers will likewise be prevented. The motor will complete a few revolutions even though the coin is jammed, and run until the stop 40 pin 16 travels forward to engage the arm 112 which swings the depending rod 110 into engagement with the bifurcated member 104. This rotates the shaft 105, which 45 thrusts the breaker arm 108 upwardly against the lever 101 and thus breaks or opens the circuit. This causes the motor to stop, and at the same time the solenoids become deenergized, which allow all parts to 50 return to normal position ready for the next cycle of operation. The operator may then punch the button again or will remove the coin which failed to eject.

It is seen that two means are provided for controlling the circuit breaker switch 55 98—99. Upon each completed operation of the machine and after the coins have been punched therefrom, the arm 102 functions to break the circuit, and this function is not dependent upon any action on the part of 60 the operator; since the independent circuit 131 immediately connects the motor with the electric current main and excludes the key board so that the motor might run until the arm 102 moved down to impinge the lever 101.

The key board is provided with a plurality of keys variously numbered so as to secure any desired selection of coin punchers to be lifted into upward position. Any one or all of the coin punchers may be lifted by 70 selecting the proper key and depressing it to close the circuit through the electrical elements as described.

The coins are in a horizontal position in the coin trough, and when ejected fall on 75 their edges or rims. They roll down the inclined chute on their rims and finally drop vertically through the chute 5, where delivery is made at 6. This prevents the coins from sticking as they pass through 80 and from the coin chute.

This machine is adapted for use principally in banks, department stores, theaters, and many other institutions where coin must be rapidly handled to make change 85 for customers.

Having thus described my invention, what I claim as new, and desire to secure by Letters Patent is:

1. A coin delivery machine comprising, a 90 coin trough to hold coin, a coin supporting plate fixed to the bottom of the trough with a slot formed therein, a coin ejector head comprising a finger and a guide adapted to move in the slot, a rod attached to the coin 95 ejector head, means for moving the rod to eject coin from the trough, and means for stopping the movement of the rod in case the coin jams.

2. A coin delivery machine comprising, a 100 rock shaft, a plurality of coin punchers mounted thereon, coin, a gear sector journaled on the rock shaft, an arm fixed to the rock shaft, a resilient connection interposed between the arm and the gear sector, and a 105 motor adapted to run the gear sector to operate the coin punchers.

3. A coin delivery machine comprising, a coin trough with a discharge slot formed therein, a supporting plate fixed to the 110 trough and having a slot formed therein, a finger slidable in the slot, a guide made integral with the finger, a puncher arm fixed to the guide, a shaft mounting the puncher arm, arms supporting the shaft, a rock 115 shaft carrying the arms, a gear sector, an arm mounted on the shaft, a resilient connection formed between the gear sector and the arm, a driving transmission to operate the gear, and means employed to engage 120 and disengage the driving mechanism from said gear.

4. A coin delivery machine comprising, a coin trough with a discharge slot formed therein, a supporting plate fixed to the 125 trough and having a slot formed therein, a finger slidable in the slot, a guide fixed to the finger, and a puncher arm fixed to the guide, a shaft mounting said puncher arms, arms supporting the shaft, a rock shaft pro- 130

vided to mount the arms, a gear sector journaled on the rock shaft, an arm mounted on the rock shaft, a resilient connection formed between the gear sector and the 5 arm, a driving transmission to operate the gear, means employed to engage and disengage the driving transmission from said gear, and means for lifting the finger into the slot of the support plate to engage the 10 rim of a coin to be ejected.

5. A coin delivery machine comprising, a device to support stacks of coins, a frame, a rock shaft journaled in the frame, with a plurality of coin punchers operated by the 15 rock shaft, a gear sector carried by the rock shaft, and an arm carried by the rock shaft, with a resilient connection joining the arm and gear sector, a motor, a shaft connected to the motor through a universal joint, and 20 a solenoid arranged to swing the shaft into and out of engagement with the gear sector for operating the coin punchers.

6. A coin delivery machine comprising, in combination, a device to support stacks 25 of coins, a frame, a rock shaft journaled in the frame, a plurality of coin punchers operated by the rock shaft, a gear sector carried by the rock shaft, an arm carried by the shaft, a resilient connection joining the 30 arm and gear sector, a motor and electric circuit, a shaft connected to the motor with a universal joint, a solenoid adapted to swing the shaft into and out of engagement with the gear sector for operating the coin 35 punchers, means for stopping the motor by opening the circuit when the coin punchers have ejected coin, and an auxiliary circuit breaker employed to stop the motor when a coin jams in the trough.

40 7. A coin delivery machine comprising, in combination, a device for holding a plurality of stacks of coin, a plurality of coin punchers employed to operate against a single coin of each aforesaid stack, a solenoid 45 for each coin puncher with a solenoid plunger to support each coin puncher for raising and lowering said coin puncher in line with the coin, selective means employed to energize one or more solenoids to lift one or 50 more coin punchers, power means for operating the coin punchers, and means for automatically discontinuing the operation of the power means when the coin becomes jammed.

55 8. A coin delivery machine comprising, in combination, a device for holding a plurality of stacks of coin, a plurality of coin punchers employed to operate against a single coin of each aforesaid stack, a solenoid 60 for each coin puncher with a solenoid plunger for raising and lowering said coin puncher in line with the coin, selective means employed to energize one or more solenoids to lift one or more coin punchers, 65 a rock shaft carrying the plurality of coin

punchers, a gear sector freely journaled on said rock shaft, an arm fixed to the rock shaft, a resilient connection joining the arm and gear sector together, a drive shaft carried on a universal joint, a worm mounted 70 on the drive shaft to engage the gear sector, a lifting mechanism employed to swing the drive shaft up and down to engage and disengage the worm with the gear sector, and a solenoid employed to operate the lifting 75 mechanism.

9. A coin delivery machine comprising, in combination, a device for holding a plurality of stacks of coin, a plurality of coin punchers employed to operate against a single coin of each aforesaid stack, a solenoid for each coin puncher with a plunger for raising and lowering said coin puncher in line with the coin, selective means employed to energize one or more solenoids to lift one 80 or more coin punchers, a rock shaft carrying the plurality of coin punchers, a gear sector freely journaled on the rock shaft, an arm fixed to said shaft, a resilient connection joining the arm and gear sector together, a stop pin fixed on the gear sector, a swinging member carried by the arm in line with the stop pin, a motor supplied by a circuit main, a circuit breaker in series with the circuit main, and means engageable 85 with the swinging member to open the circuit breaker in case a coin jams.

10. A coin delivery machine comprising, in combination, a device to hold a plurality of stacks of coin, a plurality of coin punchers to engage a single coin of each aforesaid stack, an electro selective means associated with each coin puncher to lift it in line with the coin to be engaged, a shaft mounting the plurality of coin punchers, a 100 motor for revolving the shaft, a circuit main to supply the motor with current, a circuit breaker switch in series with the circuit main, means for opening the circuit breaker switch when the coin punching action has 105 been completed by the coin punchers, and auxiliary means employed for opening the circuit breaker switch in case a coin jams.

11. A coin delivery machine comprising, a coin holder means, a coin ejector operated relatively with the coin holder, a rock shaft mounting the coin ejector, a gear on the rock shaft, an arm on the shaft, a resilient link connection between the gear and arm, a power shaft for driving the gear, a solenoid disposed beneath the ejector with a plunger in the solenoid to support the ejector, a locking head to clamp the plunger, and means for operating the locking head to clamp the plunger. 115

12. A coin delivery machine comprising, a coin holder means, a coin ejector movable relatively with the coin holder, a shaft mounting the coin ejector, a gear on the shaft, an arm on the shaft, a resilient link 120

connection between the gear and arm, a power shaft for driving the gear, a solenoid disposed beneath the ejector, with a plunger in the solenoid to support the ejector, a locking head to clamp the plunger, means for actuating the locking head to clamp the plunger, a circuit main for supplying the motor, and for supplying the solenoid, a circuit opener in the circuit main, and means 10 for opening the circuit opener after the coin puncher operates.

13. A coin delivery machine comprising, in combination, a coin holder means, a coin ejector operated relatively with the coin holder, a shaft mounting the coin ejector, a gear on the shaft, an arm on the shaft, a resilient link connection between the gear and arm, a power shaft for driving the gear, a solenoid disposed beneath the ejector, with 15 a plunger in the solenoid to support the ejector, a locking head to clamp the plunger, a circuit main for supplying the motor, and for supplying the solenoid, a circuit breaker in the circuit main, means for opening the 20 circuit breaker when the coin puncher operates, and an auxiliary appliance for opening the circuit breaker if a coin jams.

14. A coin delivery machine comprising, a coin holder means, a coin ejector operated 30 relatively with the coin holder, a rock shaft mounting the coin ejector, a gear on the rock shaft, an arm on the rock shaft, a resilient link connection between the gear and arm, a power shaft for driving the 35 gear, a solenoid disposed beneath the ejector, a plunger in the solenoid to support the ejector, a locking head to clamp the plunger, a cross shaft, an arm fixed on the cross shaft to engage the locking head, 40 a lift arm to operate the cross shaft, and a cam on the rock shaft to raise the lift arm.

15. A coin delivery machine comprising, in combination, a coin trough with slots formed therein, a plurality of coin punchers 45 reciprocatively mounted in the slots, an electro controlled means for raising and lowering the coin punchers in the slots, a motor for operating the coin punchers, a current main for supplying the motor, a 50 circuit breaker in the current main, and means for opening the circuit breaker when the machine completes its delivery of coin or when a coin jams.

16. A coin delivery machine comprising, 55 in combination, a coin trough with slots formed therein, a plurality of coin punchers reciprocatively mounted in the slot, an electro controlled means for raising and lowering the coin punchers in the slots, a 60 motor for operating the coin punchers, and a resilient connection interposed between the motor and the coin punchers to allow the motor to complete its run in case a coin jams.

65 17. A coin delivery machine comprising,

in combination, a coin trough with slots formed therein, a plurality of coin punchers reciprocatively mounted in the slots, an electro controlled means for raising and lowering the coin punchers in the slots, a 70 motor for operating the coin punchers, a resilient connection interposed between the motor and the coin punchers to allow the motor to complete its run in case a coin jams, a circuit for supplying current to the 75 motor, a circuit breaker in the circuit, and means for opening the circuit breaker when the coin is ejected.

18. A coin delivery machine comprising, in combination, a coin trough with slots 80 formed therein, a plurality of coin punchers reciprocatively mounted in the slots, an electro controlled means for raising and lowering the coin punchers in the slots, a 85 motor for moving the coin punchers, a resilient connection interposed between the motor and the coin punchers to allow relative movement between the motor and the coin punchers, a circuit for supplying current to the motor, a circuit breaker in the 90 circuit, means for opening the circuit breaker when the operation of the machine is interrupted, a contact means for simultaneously starting the motor, and for energizing the electro controlled means, and an 95 independent circuit for supplying current to the motor to run said motor in case the contact means is released.

19. A coin delivery machine comprising, in combination, a coin trough with slots 100 formed therein, a plurality of coin punchers slidably mounted in the slots, an electro controlled means for raising and lowering the coin punchers in the slots, a motor for operating the coin punchers, a resilient 105 connection interposed between the motor and the coin punchers to allow the motor relative movement with the coin punchers, a circuit for supplying current to the motor, a circuit breaker in the circuit, 110 means for opening the circuit when the operation of the machine is interrupted, a contact means for simultaneously starting the motor and for energizing the electro controlled means, an independent circuit for 115 supplying current to the motor to run said motor in case the contact means is released, and means employed to open the independent circuit when the machine has operated.

20. A coin delivery machine comprising, 120 in combination, a coin trough with slots formed therein, a plurality of coin punchers slidably mounted in the slots, an electro controlled means for raising and lowering the coin punchers in the slots, a motor for operating the coin punchers a resilient connection interposed between the motor and the coin punchers to allow the motor a movement relatively with the coin punchers, a circuit for supplying current to the motor, 125 130

a circuit breaker in the circuit, means for opening the circuit when the operation of the machine is interrupted, a contact means for simultaneously starting the motor and 5 for energizing the electro controlled means, an independent circuit for supplying current to the motor to run said motor in case the contact means is released, means employed to break the independent circuit 10 when the machine has operated, and means for keeping the circuit open as long as the contact means functions.

21. A coin delivery machine comprising, a coin trough, a plurality of coin punchers 15 engageable with said trough, a shaft to which is pivotally connected the plurality of coin punchers, support arms carrying the shaft, a rock shaft mounting the support arms, a gear section journaled on the rock 20 shaft, an arm fixed to the rock shaft, means employed to permit relative movement between the arm and the gear sector, a swinging link depending from the arm, an electric motor supplied from a current main, a 25 drive shaft propelled by the motor, a universal joint fitted in the drive shaft, a driving member fixed on the drive shaft, means for engaging and disengaging the driving member with the gear sector, a circuit 30 breaker switch included in the current main, and means engageable with the swinging link to open the circuit breaker switch in case a coin jams.

22. A coin delivery machine comprising, a coin trough, a plurality of coin punchers 35 engageable with the trough, a rock shaft supporting the plurality of coin punchers, an electromagnet employed to lift each coin puncher in engagement with coin to be ejected, a gear sector on the rock shaft, an arm fixed to the rock shaft, a coil spring connecting the arm and gear sector, a motor, and a drive shaft, a gear fixed to the drive shaft to engage with the sector, a current 40 supply main to run the motor, a circuit breaker switch in the current supply main, and a circuit breaker arm fixed to the rock shaft to open the circuit breaker switch.

23. A coin delivery machine comprising, a coin trough, a plurality of coin punchers 50 engageable with the trough, a rock shaft mounting the plurality of coin punchers, an electromagnet employed to lift each coin puncher in engagement with coin to be ejected, a gear sector on the rock shaft, an arm fixed to the rock shaft, a coil spring connecting the arm and gear sector, a motor, a drive shaft connected with the motor, and a gear fixed to the drive shaft to engage with 55 the sector, a current supply main to run the motor, a circuit breaker switch in the current supply main, a circuit breaker arm fixed to the rock shaft to open the circuit breaker switch, and auxiliary means for opening the

circuit breaker switch in case a coin fails to 65 be ejected.

24. A coin delivery machine comprising, a coin trough, coin punchers engageable therewith for ejecting coin, a rock shaft mounting the coin punchers, a solenoid with a 70 plunger positioned underneath each coin puncher to lift said puncher into engagement with the coin trough, a locking head, a shaft, depending arms fixed thereto and engaging the locking heads to press said heads 75 against the plunger, a lift arm fixed to the shaft, a solenoid, a plunger associated with the solenoid and connected with the lift arm adapted to raise said lift arm, a cam engageable with the lift arm, a gear on the 80 rock shaft employed to operate the coin punchers, and a drive shaft for moving the gear.

25. A coin delivery machine comprising, a coin trough, a plurality of coin punchers 85 engageable with said coin trough, a solenoid and a plunger positioned underneath each coin puncher adapted to lift said coin punchers into engagement with the coin trough, an electric motor for operating the 90 coin punchers, a circuit main to supply said motor, said circuit main connecting in parallel with the plurality of solenoids, a circuit breaker switch included in the circuit main, and means for opening the circuit 95 breaker switch after the motor has completed its cycle of operation.

26. A coin delivery machine comprising, a device to hold a plurality of stacks of coin arranged according to denominational 100 value, said device being provided with guide slots, a plurality of coin ejector heads slidably confined within the guide slots, rods fixed to the ejector heads, means for actuating the rods, a plurality of solenoids arranged beneath the rods, with solenoid plungers provided to support said rods, an electric circuit main connecting with the solenoids, and a key board provided to control the energization of one or more solenoids to lift one or more ejector heads in the aforesaid guide slots.

27. A coin delivery machine comprising, in combination, a device to hold a plurality of stacks of coin arranged according to denominational value, said device being provided with guide slots, a plurality of coin ejector heads slidably confined within the guide slots, rods fixed to the ejector heads, means for actuating the rods, a plurality of 115 solenoids arranged beneath the rods, solenoid plungers provided to support said rods, an electric circuit main connecting with the solenoids, a key board provided to control the energization of one or more solenoids to lift one or more ejector heads in the aforesaid guide slots, a circuit breaker switch included in the circuit main, and

mechanical means for opening said circuit switch simultaneously with the coin ejecting action of the ejector heads.

28. A coin delivery machine comprising, a device to hold a plurality of stacks of coin arranged according to denominational value, said device being provided with guide slots, a plurality of coin ejector heads slidably confined within the guide slots, rods fixed to the ejector heads, means for actuating the rods, a plurality of solenoids arranged beneath the rods, solenoid cores provided to support said rods, an electric circuit main connecting with the solenoids, a key board provided to control the energization of one or more solenoids to lift one or more ejector heads in the aforesaid guide slots, a circuit breaker switch included in the circuit main, mechanical means for opening said circuit breaker switch simultaneously with the coin ejecting action of the ejector heads, and an electromagnetic element employed to coöperate with the aforesaid mechanical means to hold said circuit breaker switch open in case the key board functions for a longer time than necessary to operate the system.

29. A coin delivery machine comprising, a device for holding coins arranged according to denominational value in tiers, a plurality of devices to eject a single coin from each tier, a motor to operate the plurality of devices, a circuit main to supply the motor with current, a key board in series with said circuit main to close said circuit, a relay circuit connected in parallel with the motor and key board to furnish current to said motor in case the key board does not function sufficiently long to operate the motor to eject coin, and a mechanically operated circuit breaker means included in series with said circuit main to open the circuit and hold it open in case the key board functions for a period longer than necessary to complete the coin ejecting movement.

30. A coin delivery machine comprising, in combination, a device for holding coins arranged according to denominational value in tiers, a plurality of devices to eject a single coin from each tier, a motor to operate the plurality of devices, a circuit main to supply current to the motor, a key board in series with the circuit main to close said circuit, a relay circuit connected in parallel with the motor and key board to furnish current to said motor in case the key board does not function sufficiently long to run the motor to eject coin, a mechanically operated circuit breaker means included in series with said circuit main, and an electromagnetic device connected in parallel with the key board and with the circuit main for holding the aforesaid mechanically operated circuit breaker means open in case the key board functions for a period longer than necessary to operate the system.

31. A coin delivery machine comprising, in combination, a coin rack or trough employed to hold several stacks of coins arranged in tiers according to denominational value, with guide slots provided in said coin rack or trough, a coin ejector head slidably confined in each slot, a rod connected to the ejector head, a shaft carrying the rod, a motor employed to move the shaft, an electric circuit main to run the motor, a solenoid associated with each rod and connected with the circuit main, a plunger slidably confined in each solenoid so as to support said rod on top of said plunger to confine each ejector head in its respective guide slot, and a key board connected with the circuit main and consisting of means for selectively energizing one or more solenoids and simultaneously starting the motor.

32. A coin delivery machine comprising, a coin rack or trough employed to hold several stacks of coins arranged in tiers according to denominational value, with guide slots provided in said coin rack or trough, a coin ejector head slidably confined in each slot, one end of a rod fixed to each ejector head, a shaft carrying the other end of said rod, a motor employed to move the shaft, an electric circuit main to run the motor, a solenoid associated with each rod and connected with the circuit main, a plunger reciprocatively confined in each solenoid so as to support said rod on top of said plunger to confine each ejector head in its respective guide slot, a key board connected with the circuit main and consisting of means for selectively energizing one or more solenoids and for simultaneously starting the motor, and a solenoid connected in parallel with the circuit main and acting to lock the solenoid plungers.

33. A coin delivery machine comprising, a coin rack or trough employed to hold several stacks of coins arranged in tiers according to denominational value, with guide slots provided in said coin rack or trough, a coin ejector head slidably confined in each slot, one end of a rod fixed to each ejector head, a shaft pivotally mounting the other end of the rod, a motor employed to move the shaft, an electric circuit main to run the motor, a solenoid connected to the circuit main and associated with each rod, a plunger reciprocatively confined in each solenoid so as to support said rod on top of said plunger to confine each ejector head in its respective guide slot, a key board connected with the circuit main and consisting of means for selectively energizing one or more solenoids and for simultaneously starting the motor, and a mechanical circuit breaker means included in the electrical current main for opening aforesaid current main to stop the motor when the coin punching operation has been completed.

34. A coin delivery machine comprising,

a coin rack or trough employed to hold several stacks of coins arranged in tiers according to denominational value, with guide slots provided in said coin rack or trough, a 5 coin ejector head slidably confined in each slot, one end of a rod fixed to each ejector head, and a shaft pivotally mounting the other end of the rod, a motor employed to move the shaft, an electric circuit main to 10 run the motor, a solenoid associated with each rod and connected with the circuit main, a plunger reciprocatively confined in each solenoid so as to support said rod on top of said plunger to confine each ejector head in its respective guide slot, a key board 15 connected with the circuit main and consisting of means for selectively energizing one or more solenoids and simultaneously starting the motor, a mechanical circuit 20 breaker means included in the electrical current main for opening aforesaid current main to stop aforesaid motor when the coin punching operation has been completed, and an electromagnetic element employed 25 to hold the mechanical circuit breaker means open in case the key board continues to hold the circuit main closed.

35. A coin delivery machine comprising, a coin rack or trough employed to hold several stacks of coins arranged in tiers according to denominational value, with guide slots provided in said coin rack or trough, a coin ejector head slidably confined in each slot, one end of a rod fixed to each ejector head, a shaft mounting the other end of this rod, a motor employed to move the shaft, an electric circuit main to run the motor, a solenoid employed for each rod and connected with the circuit main, a plunger reciprocatively confined in each solenoid so as to support said rod on top of said plunger to confine each ejector head in its respective guide slot, a key board connected with the circuit main and consisting of 35 means for selectively energizing one or more solenoids and simultaneously starting the motor, a mechanical circuit breaker means included in the electrical current main for opening the aforesaid current main to stop 40 the aforesaid motor when the coin punching operation has been completed, an electromagnetic element employed to hold the mechanical circuit breaker means open in case the key board continues to hold the circuit main closed, and a relay circuit employed to furnish current to the motor in case the key board fails to close the circuit main for a period sufficiently long to allow the motor to complete its period of operation.

60 36. A coin delivery machine comprising, a means employed to hold stacks of coin, a device employed to eject coin therefrom, said device carried upon a rock shaft, a gear mounted on the rock shaft, an arm mounted 65 on the shaft, a resilient link connection be-

tween the gear and the arm to permit relative movement of the gear and the arm so as to rotate the shaft, a drive shaft engageably associated with the gear, said drive shaft fitted with a universal joint at one end thereof, a lifting mechanism associated with the other end of said drive shaft, a motor for revolving aforesaid drive shaft, and a solenoid employed to control the lifting mechanism to engage the drive shaft with the gear when the motor starts.

70 37. A coin delivery mechanism of the type comprising a coin-holding device, a coin-ejecting mechanism, and a motor for driving the mechanism, characterized by having an automatic cut-out apparatus for stopping the motor in case coins in the mechanism become jammed.

80 38. A coin delivery mechanism comprising a coin holder, a coin ejector, a power shaft operatively connected to said ejector, an electric motor connected to said shaft, having a supply circuit, a circuit breaker in said supply circuit, means connected with said shaft to open said circuit at a predetermined point in the movement of said shaft, resilient means for permitting the movement of said motor when the movement of the ejector is obstructed, and means operated by said resilient means to operate the circuit breaker when the movement of the ejector is obstructed.

85 39. A coin delivery mechanism comprising a reciprocating element, a motor for driving said element, a resilient connection therebetween, a motor circuit, a circuit breaker in said circuit, means connected to said motor to operate the circuit breaker at a predetermined point in the movement of said motor, and means associated with said 90 resilient means to operate the circuit breaker when the movement of the reciprocating element is obstructed.

95 40. A coin delivery mechanism comprising a coin holder, a coin ejector having inoperative and operative positions, electro-magnetic means for moving said ejector to its operative position, mechanical means for retaining said ejector in its operative position, and means for causing the actuation of 105 the first-mentioned means before the actuation of the second-mentioned means.

110 41. A coin delivery machine comprising a coin holder having a slot in its bottom, a coin ejector adapted to move in the slot, 115 means to actuate said ejector, and means for stopping the movement of the actuating means when the movement of the ejector is obstructed.

120 42. A coin delivery machine comprising a 125 rock shaft, a plurality of coin ejectors mounted thereon, a gear sector journaled on said shaft, an arm fixed to the shaft, a resilient connection between the arm and the sector, and a motor adapted to actuate the sector. 130

43. A coin delivery machine comprising a coin holder, an ejector rod coöperating therewith, a shaft supporting one end of said rod, arms supporting the shaft, a rock 5 shaft carrying the arms, a gear sector, an arm mounted on the shaft, a resilient connection between the sector and the arm, a driving transmission to operate the gear, and means employed to engage and disengage 10 the driving mechanism from said gear.

44. A coin delivery machine comprising a coin holder, a frame, a rock shaft journaled in the frame, a coin ejector operated by said rock shaft, a gear sector journaled on the 15 rock shaft, an arm carried by the rock shaft, a resilient connection between the arm and the sector, a motor, a shaft connected to the motor, and a solenoid arranged to swing the shaft into and out of engagement with the 20 sector for operating the ejector.

45. A coin delivery machine comprising a coin holder, a coin ejector, a power shaft op-

eratively connected to said ejector, a motor for driving said shaft, a resilient connection between said motor and said shaft, 25 means for engaging and disengaging the motor and shaft, and means operated by the motor to actuate the disengaging means when the motor has reached a predetermined point in its travel and whenever the movement of the ejector is obstructed.

46. A coin delivery machine comprising a coin holder, a coin ejector, electro-magnetic means associated with said ejector to move it into operative position, a shaft connected 35 to said ejector, a motor for revolving the shaft, a supply circuit for said motor, a switch in said circuit, mean for opening said switch when the ejection of the coin has been completed, and auxiliary means for opening the switch whenever the movement of the ejector is obstructed.

CARL McDERMOTT.
